UNITED STATES PATENT OFFICE.

LOUIS C. WAGNER, OF NEW YORK, N. Y.

DESIGN FOR A CIGAR BAND OR WRAPPER.

No. 38,750.

Specification for Design.

Patented Aug. 20, 1907.

Application filed July 18, 1907. Serial No. 384,490. Term of patent 7 years.

To all whom it may concern:

Be it known that I, LOUIS C. WAGNER, a citizen of the United States, residing at New York city, county of New York, State of New York, have invented a new, original, and ornamental Design for a Cigar Band or Wrapper.

The design is illustrated in the accompanying drawing and shows a face elevation thereof.

I claim:

The ornamental design for a cigar band or wrapper as shown.

LOUIS C. WAGNER.
